GARMENT CLOSURE

Joseph J. Kispert, Mount Carmel, Conn.

Application June 10, 1943, Serial No. 490,353
In Canada October 23, 1942

7 Claims.

(Cl. 2—39)

This invention relates to apparel and more specifically to a closure particularly adapted for a corset, girdle or foundation garment but not restricted to such garments.

The present application constitutes a continuation in part of my prior application for patent on a corset, Ser. No. 400,501, filed June 30, 1941, and a continuation of my prior application for patent on a corset, Ser. No. 479,259, filed March 15, 1943.

One object of the invention is to provide a garment of this character with improved closure means consisting of soft portions adapted to be drawn toward each other by laces engaged with hooks carried by reinforcements extending along margins of the closure portions, said reinforcements constituting soft stays for the garment as well as serving as flexible hook carriers.

Another object of the invention is to provide closure portions of the garment with stays which are formed entirely of soft fabric or other suitable material and so stitched that while the stays will remain pliable, they will have sufficient stiffness to reinforce marginal portions of the garment along an opening at the front, back or side thereof and cause the garment to exert confining pressure to portions of the body against which they bear.

Another object of the invention is to provide the improved stays with lacing hooks so mounted that they are embedded in the stays, the stays being provided with lines of stitching extending transversely of the stays in such relation to the hooks that each hook has its shank confined in a pocket which tapers toward its outer end. It will thus be seen that the stitching defines pockets in which the hooks are located and, since portions of the stitching extend transversely across the stays at opposite sides of each hook, the stays will be greatly reinforced without impairing the flexibility thereof and the garment will be very comfortable.

Another object of the invention is to provide the garment with stays which reinforce the same and, while permitting the abdomen to be compressed and uplifted, will not apply pressure at their ends to the abdomen and cause discomfort when a person wearing the garment leans over or is in a sitting position.

In the accompanying drawings:

Fig. 1 is a front elevation of a corset provided with a closure of the improved construction.

Fig. 2 is a fragmentary view showing the

lacing released and a closure flap partially turned outwardly.

Fig. 3 is a fragmentary view on an enlarged scale looking at the outer face of the improved stay.

Fig. 4 is a perspective view of the improved stay with portions thereof in section and portions broken away.

Fig. 5 is a sectional view on an enlarged scale, taken on the line 5—5 of Fig. 1.

Fig. 6 is a fragmentary sectional view on the line 6—6 of Fig. 5.

Fig. 7 is a perspective view of a hook.

Fig. 8 is a view of a corset having its lacing stays reinforced with a modified arrangement of stitching.

Fig. 9 is an enlarged fragmentary view of the corset illustrated in Fig. 8.

Fig. 10 is a sectional view on an enlarged scale on the line 10—10 of Fig. 9.

Fig. 11 is a view similar to Fig. 9, showing another modified arrangement of reinforcing stitching for the lacing stay.

In Fig. 1, there has been shown a garment having a front closure of the improved construction. This garment has been illustrated as a girdle, but it is to be understood that it may be a corset or any other garment. It is also to be understood that while the girdle has been shown open at the front, it may be open at the back or along a side and that said opening may extend the full length of the garment or for only a portion of its length.

The garment illustrated is provided with outer closure flaps 2 which are drawn tightly into place across inner flaps or closure portions 3 by laces 4 and 5, and have smooth compressing engagement with the inner flaps when the laces are tightened and secured. If desired, the inner flaps 3 may be omitted, or a shielding strip or sheet of thin fabric substituted in lieu thereof and sewed along one or both of its side edges. Also, instead of providing separately formed closure flaps 2 and sewing them to side edges of the body of the garment by seams 6, the closure flaps may constitute portions of the garment body at opposite sides of the opening.

The important features of this improved garment are the closure flaps or equivalent portions of the garment body and the stays 7 which extend along their free side edges and constitute reinforcements for the closure elements as well as carriers for the hooks 8 with which the laces 4 are engaged when the garment is applied and tightened about the wearer. The hooks are

carried by a strip 9 of fabric and, in the illustration, these hooks are formed of sheet metal and each has its shank provided with tongues 10 and passed through the strip and clinched to firmly hold the hook to the strip. The hooks extend transversely of the strip and their free end portions, which are bent to form bills 11, project from the strip also from the outer free side edges of the stay. The strip 9 is enclosed in a casing 12 formed from a folded strip of fabric and this casing is held to the strip 9 by one or more lines of stitching 13 extending longitudinally thereof near its inner side edge. Openings 14 are formed at the fold line of the casing 12 and the hooks project outwardly through these openings, as shown clearly in Figs. 4 and 5. While the hooks have been shown as formed of sheet metal, it is to be understood that they may be formed of wire or other suitable material and provided with eyes to receive staples or equivalent fastening means, instead of the tongues 10.

Before the core, formed of the hook-carrying strip 9 and its casing 12, is applied to the closure flap 2 or equivalent portion of the garment, the free side edge portion of the flap is folded inwardly back upon itself, as shown at 15, to form a smooth and ravel-proof outer side edge for the closure flap and a facing 16 of double thickness, formed from a folded strip of fabric, is then placed against the fold 15 to which it is sewed by stitching 18, the fold 15 and facing 16 being flattened out during the stitching operation and then refolded. The core is then set in place between fold 15 and the facing with the hooks projecting outwardly through spaced openings in the stitching and lines of stitching 18 passed through the flap 2 and inner side portions of the core and facing to firmly hold these elements together. Before the closure flap, core and facing are sewed to each other by the lines of stitching 17, the companion lacing 4 is applied with its inner end portion folded to engage transversely about the core and tucked between the fold 15 and body of the closure flap. The smooth and unbroken outer side edge of the facing 16 formed by the fold or crease in the fabric strip from which the facing is formed, is disposed flush with the folded outer side edge of the closure flap and the closure will thus be provided with a smoothly finished edge. Stitching constituting a main feature of the improved construction, is then applied.

This stitching, indicated in general by the numeral 19, extends diagonally back and forth across the stay between the hooks, as shown at 20, and between the diagonally extending portions 21 of the line of stitching are other portions 21 and 22 which extend longitudinally of the stay, the inner longitudinally extending portions 21 being near the inner side edge of the strip 9 and its casing 12 and the outer longitudinally extending portions 22 being close to the folded outer side edges of the closure flap and facing 16. Referring particularly to Figs. 3 and 4, it will be seen that the portions 20 of the line of stitching 19 extend transversely across the stay at opposite sides of the hooks in such diagonal relation to each other that each hook is disposed between lines of stitching 20 which converge outwardly from ends of the stitching 21 to ends of the stitching 22. These outwardly converging lines of stitching 20 serve to reinforce the stay without interfering with longitudinal flexing thereof and cooperate with each other to divide the stay into transversely extending pockets 23 in which the hooks 75 responding to the stitching 19, has the portions

are disposed. The pockets are gradually reduced in width toward their outer ends to reduce to a minimum any danger of the hooks being dragged outwardly from the pockets and, since the portions 22 of the stitching terminate in spaced relation to each other at opposite sides of outer ends of the pockets, the outer ends or mouths 24 of the pockets will be left open to accommodate the shanks of the hooks occupying the pockets. It will thus be seen that the stays will be greatly reinforced but still have pliability to permit them to be somewhat distorted when the lacings are tightened and also prevent lower ends of the stays from digging into a person's abdomen when assuming a stooping or sitting position.

In Figs. 8, 9 and 10 of the drawings, there has been illustrated a modified embodiment of the invention. The corset 25 may be of conventional formation and has inner closure flaps 26 carrying interengaging fasteners 27 for connecting the flaps with each other when the garment is applied. The closure portions 28 of the garment may be in the form of outer flaps or constitute portions of the body of the garment and, along their free side edges, are provided with flexible stays 29 corresponding to the stays 1. Each stay 29 has a core consisting of a strip of fabric 30 carrying lacing hooks 31, which have been shown formed of bent wire and stapled or otherwise firmly secured to the core and a casing 32 of fabric corresponding to the casing 12 and stitched to the strip 30. The marginal portion of the closure 28 is folded inwardly, as shown at 33, and at the opposite side of the core is a facing strip 34 formed of a folded strip of fabric corresponding to the facing 16 and secured near its inner side edge by lines of stitching 35. In these respects, the flexible stay is similar in construction to that illustrated in Figs. 1 through 7, except that the hooks are formed of bent wire strands instead of being formed of sheet metal.

The stitching 36 is, however, somewhat different from the corresponding stitching 19. This stitching 36 has portions 37 extending diagonally across the stay, and upon reference to Fig. 9, it will be seen that while the stitching 19 and the stitching 36 both follow zig zag paths back and forth across the stays and divide the stays into sections or pockets in which the hooks are located, the diagonally extending portions 37 of the stitching 36 at opposite sides of the hooks diverge toward the free side edge thereof. Inner ends of the portions 37 of the stitching are connected by portions 38 which correspond to the portions 21 of the stitching 19. In both cases, the stitching consists of a continuous line of stitching extending back and forth across the stay in a zig zag path with the portions at opposite sides of the hooks extending diagonally. The stays are thus greatly reinforced, but pliable, and the hooks will be firmly held to the stays and prevented from being easily torn loose when subjected to strains.

In Fig. 11 there has been shown a corset or similar garment 39 having companion inner closure portions 40 and outer closure portions 41 corresponding to the closure portions 26 and 29. A flexible or pliable stay 42, formed of fabric, extends along the outer free side edge of the outer closure portion 41 and carries hooks 43 which may be formed of wire, sheet metal, or other suitable material. The stay 42 is of the same construction illustrated and described heretofore except that the line of stitching 44 corresponding to the stitching 19, has the portions

45 extending transversely across the stay between ends of the portions 46 and 47, disposed at right angles to the length of the stay instead of diagonally across the stay. This stitching follows a zig zag path back and forth across the stay and reinforces the stay as well as dividing it into a plurality of portions, each of which carries a lacing hook.

It has been found that having the stitching follow a zig zag path back and forth across the stay so as to divide it into distinct portions each carrying a hook, greatly strengthens the stay, preventing wrinkling thereof, and eliminates likelihood of the hooks being torn loose from the stay; and also permits the stay to bend in all directions and makes the corset more comfortable as it may be laced right to the bottom of the abdomen and hold the abdomen compressed and uplifted without the lower end of the stay digging into the abdomen when a person wearing the corset is seated or bending over.

Having thus described the invention what is claimed is:

1. In a garment, companion closure portions having free outer side edges, stays formed of soft pliable material mounted along the outer side edges of said closure portions, facing strips covering said stays, lacing hooks carried by said stays and projecting outwardly from the stays and the facing strips, and lines of stitching for reinforcing the stays extending transversely and diagonally across the stays between the hooks and dividing the stays into transversely extending portions each carrying a hook.

2. In a garment, companion closure portions having free outer side edges, stays formed of soft pliable material mounted along the outer side edges of said closure portions, facing strips covering said stays, lacing hooks carried by said stays and projecting outwardly from the stays and the facing strips, and lines of stitching having portions extending back and forth across the stays between the hooks to reinforce the stays and divide them into transversely extending portions, each carrying a hook.

3. In a garment including closure portions normally spaced from each other and each having a free side edge, stays extending along said free side edges of said closure portions, said stays being formed of soft pliable material, lacing hooks carried by said stays and projecting outwardly therefrom, and lines of stitching for reinforcing the stays extending transversely and diagonally across the stays with the hooks each located between a pair of transversely extending lines of stitches, the lines of stitches at opposite sides of each hook converging toward their outer ends and dividing the stays into hook-carrying portions each tapered toward its outer end.

4. In a garment, companion closure portions

having free outer side edges, stays formed of soft pliable material mounted along the outer side edges of said closure portions, facing strips covering said stays, lacing hooks carried by said

6 stays and projecting outwardly from the stays and the facing strips, and lines of stitching for reinforcing the stays having portions extending longitudinally of the stays in staggered relation to each other and other portions extending transversely and diagonally across the stays between ends of the longitudinally extending portions and dividing the stays into pockets tapered toward their outer ends and in which the hooks are located.

10 5. In a garment, closure portions normally spaced from each other and having inturned folds along their free side edges, soft pliable stays along the free edges of said closure portions, each stay having a core of soft pliable material enclosed in an envelope of soft pliable material,

20 hooks carried by the core and projecting from the outer side edge thereof and beyond the free side edge of the companion closure portion, a facing for said core formed from a folded strip of soft pliable material, the core and facing being secured by longitudinal lines of stitching passing through their side edge portions, and lines of stitching for reinforcing said stays having inner and outer portions extending longitudinally of the stays and other portions extending transversely across the stays between ends of the longitudinal stitching and dividing the stays into pockets each having a hook therein.

25 6. A closure for corsets and similar garments, having a pair of cooperating flaps, a lacing hook mounting in each of said flaps, said mounting including a flexible tape, hooks mounted on said tape at spaced intervals, reinforcing fabric folded upon itself to surround the outer edge and sides of said tape, said fabric having apertures along its fold to accommodate said hooks, a line of stitching securing the inner edges of said tape and said reinforcing member to said flap, and a line of stitching passing through said tape, said

40 45 reinforcing fabric and said flap and following a zig zag path having portions extending back and forth transversely across the mounting between the hooks and dividing the mounting into portions each carrying a hook.

50 55 7. A lacing hook mounting including a flexible member, hooks mounted on said flexible member, a reinforcing member surrounding said flexible member and stitched thereto, an outer layer of fabric on either side of said reinforcing member, and a line of zig zag stitching between and around said hooks to maintain said flexible member, reinforcing member and covering material in proper relation.

JOSEPH J. KISPERT.
